UNITED STATES PATENT OFFICE.

OTTO H. HAKE, OF WASHINGTON, MISSOURI, ASSIGNOR OF ONE-HALF TO
ARTHUR MILLER, OF SAME PLACE.

HOSE-SUPPORTER.

SPECIFICATION forming part of Letters Patent No. 655,439, dated August 7, 1900.

Application filed October 4, 1898. Serial No. 692,622. (No model.)

To all whom it may concern:

Be it known that I, OTTO H. HAKE, a citizen of the United States, and a resident of Washington, in the county of Franklin and State of Missouri, have invented a new and useful Hose-Supporter, of which the following is a specification.

My invention is an improvement in hose-supporters, and relates more especially to that class which are used for supporting men's half-hose and comprise usually an elastic band or garter and a cord or other flexible connection for supporting the hose therefrom.

The object of my invention is to provide a hose-supporter of this general character which shall be simple and cheap in construction, effective in use, and possess the more important advantage of being more durable and lasting than like supporters. To this end my invention contemplates a construction and arrangement which will dispense entirely with the use of gum-elastic bands and cords, the necessary elasticity being furnished by a spring-wire connection, to which the non-elastic leg-encircling band is attached at its ends and through the intervention of said spring-wire connection is permitted the required adjustability or give to accommodate itself to the movements of the muscles of the leg and relieve any binding thereon.

It is well known that the hose-supporters of this character which are in general use soon become worn out or unfit, owing to the rapid deterioration of the gum-elastic band employed, coupled with the undue wear which comes upon the cord, and in order to overcome these weaknesses and provide a strong and durable hose-supporter containing the required elasticity and susceptible to little or no wear I have devised one which is herein fully shown and described, and particularly set forth in the appended claims.

In the accompanying drawings, forming a part hereof, Figure 1 is a view showing the application of my invention. Fig. 2 is an enlarged detail view of the spring-wire connection. Fig. 3 is a similar view of a modification of said spring-wire connection, including a modified form of clasp.

In carrying out the principal or material part of my invention—to wit, the spring-wire

connection, which is interposed between the leg-encircling band and metallic loop to provide the required elasticity or give—the same is preferably made up as shown in Figs. 1 and 2. In this preferred form the single piece of wire of which the device is constructed is first bent or coiled centrally to form two coils *a a*, from the opposite sides of which the terminal portions *A A* of the wire are curved inward and crossed, while the ends are bent into loops or eyes *b b'*. This particular construction of the spring-wire connection provides two spring members *A A*, and by attaching the ends of the leg-encircling band *H* thereto said band may be made of non-elastic material and will derive its play or give from the spring movement of said members, permitting the band to conform to the movement of the muscles without binding. One end of this band is placed in looped engagement with one of the spring members, being provided with the usual adjusting-slide *h*, while the other end carries a hook *i* for detachably connecting it to the other spring member. The band can therefore be adjusted to accommodate the leg of the wearer, and it will be here noted that there being no perceptible wear or deterioration of the spring-wire connection and no stretching of the band a readjustment will not be required, as in the case of gum-elastic bands or cords.

In order to provide an attachment for engaging the hose, the spring-wire connection carries a metallic loop *K*, as shown in Figs. 1 and 2. This metallic loop presents a keyhole-slot *k*, which is open at one side to facilitate the insertion of a portion of the hose thereinto, and said loop has an extension *K'*, by which it is attached to the spring-wire connection, the said extension being bent upon the lower part of the coils *a a*.

The movement of the spring members *A A* is limited by a collar or sleeve *d*, which encircles both of said members where they cross each other and by sliding up and down on the members permits the required movement thereof.

When the device is adjusted to the leg through the intervention of the band or garter *H*, the ends of the spring members *A A* should be only slightly separated, so that the

movements of the muscles while exercising the leg will be taken up and given full play through the spring movement of said members.

5 It is apparent that instead of providing the spring-wire connection with two coils, as shown and described, the same could be provided with but a single coil and probably be as effective, and, in fact, in some cases the 10 coils could be entirely dispensed with, as illustrated in the modification of the invention which I shall now proceed to describe.

In the modification, Fig. 3, the wire is first bent upon itself centrally and shaped to form 15 the open loop M, at the upper end of which the two members of the wire are tightly twisted together, as shown at m, and the terminal portions curved outward and then crossed, while the ends are bent into loops or eyes to 20 receive the band or garter, the aforesaid curved terminal members forming spring members, (designated by the letters N N and similar to those lettered A A in Figs. 1 and 2.)

Instead of the loop herein shown and described I may employ any other form of attachment device—for instance, a safety-pin or spring-clasp—but the loop is preferred, as it does not injure the hose, and the particular loop shown and described herein makes 30 provision for quickly attaching and detaching.

The give or adjustability which the leg-encircling band acquires through the intervention of the spring-wire connection is more 35 easy and positive than that had by the ordinary gum-elastic band or cord and is free from the binding and itching sensation always felt by the wearers of gum-elastics. By employing a non-elastic band the life of the same 40 is greatly increased, and as there is practically no wear whatever upon the spring-wire connection I produce a hose-supporter which is extremely durable and will not lose its 45 give or elasticity, affording at all times a uniform and proper fit after being once adjusted.

It is also apparent that in addition to its effectiveness and wearing qualities over hose-supporters of like kind my improved device presents a neater appearance and will be found to be considerably cheaper, owing to 50 the minimum cost of manufacture and maximum durability.

Having thus described my invention, I do not wish to be limited to what is herein precisely shown and described, for obvious 55 changes could be made in the shape of the spring-wire connection without sacrificing its advantages.

What I therefore claim as my invention, and desire to secure by Letters Patent, is— 60

1. A hose-supporter, comprising a spring-wire connection presenting coils and spring members crossed above the coils, the ends of said spring members being bent into loops; a collar encircling the spring members where 65 they cross; a band attached at one end to the looped end of one of the spring members, and a hook at the free end of the band for engagement with the other spring member; together with a metal loop or holding device 70 carried by the coils of the spring-wire connection, as herein shown and for the purpose set forth.

2. In a hose-supporter, the combination, of a spring-wire connection made up of a single 75 piece of wire bent to form a loop above which the two portions of the wire are twisted together, curved outward and crossed to form spring members the terminals of which are formed into loops; together with a band attached to the looped end of one of the spring members, and a hook attached to the other end of said band, substantially as shown and for the purpose set forth.

In testimony whereof I hereunto set my 85 hand.

OTTO H. HAKE.

In presence of—
H. A. HERKSTROETER,
ADOLPH J. NOELKE.
